CLAIM

The ornamental design for an illuminated display on a sequencing instrument, as shown and described.

DESCRIPTION

FIG. 1 is a front view of a first embodiment of an illuminated display on a sequencing instrument;

FIG. 2 is a front view of a second embodiment of an illuminated display on a sequencing instrument; and,
FIG. 3 is a front view of a third embodiment of an illuminated display on a sequencing instrument.

The stippling in FIGS. 1-3 represents illumination of the illuminated display.

The broken lines in the figures are included for the purpose of illustrating environmental structure and these broken lines form no part of the claimed design.
